UNITED STATES PATENT OFFICE.

DAVID KAPLAN, OF NEW YORK, N. Y.

DEVICE FOR POLYSECTING ANY GIVEN ANGLE.

1,145,369.

Specification of Letters Patent.

Patented July 6, 1915.

Application filed January 9, 1915. Serial No. 1,272.

To all whom it may concern:

Be it known that I, DAVID KAPLAN, a citizen of the United States of America, and a resident of the city of New York, borough 5 of the Bronx, and State of New York, have invented a new and useful Device for Polysecting Any Given Angle.

There are several mechanical devices for polysecting an angle, but they are cumbersome in construction and require a number 10 of adjustments before the desired angle is obtained.

The object of my device is to provide an instrument for polysecting an angle of simple construction employing the least number 15 of parts and requiring less adjustments than any of the other devices known.

One of the many advantages of my device is that it is very simple both in its construction and operation.

Another advantage is that it requires only one setting of the instrument to get the required angle.

A further advantage is that it is mathematically correct, there being no approximations in the theory of its action.

Other advantages will be apparent from the detailed description and the accompanying drawing, which forms a part of this 30 specification and in which:

Figure 1 is a plan view of my device, Fig. 2 is an elevation of my device taken on line 2-2 of Fig. 1. Fig. 3 is a section taken on line 3-3 of Fig. 1. Fig. 4 is a diagram 35 showing the method of dividing an angle into four or any even number of equal parts and Fig. 5 is a diagram showing the method of dividing an angle into five or any odd number of equal parts.

40 In the accompanying figures like numerals indicate corresponding parts in all views.

The bars 7 and 9 comprising the external limiting members and being provided with slots 8 and 10 respectively are pivoted about 45 the pin 20 so that the center lines of the slots 8 and 10 intersect at the center line of the pin 20. The bar 1 is pivoted about the pin 12 which is screwed into the bar 7. The distance between the centers of the pins 20 50 and 12 on the bar 7, as well as the distances between centers of pins 12 and 13, 13 and 14, 14 and 15, etc., are made equal, thus making the bars 1, 2, 3, 4, 5, 6, etc., equal in length. The pin 13 holds the ends of bars 55 1 and 2 together allowing them to swing about it, while at the same time the pin

itself may slide in the slot 10. Similarly the pin 14 is a pivot for the bars 2 and 3 at the same time allowing their intersection to slide in the slot 8. In a similar manner the intersections of the bars 3 and 4, 4 and 5, 5 and 6, etc., are held by the pins 15, 16, 17, etc., respectively. The bars 1, 2, 3, 4, 5 and 6 are thus interposed between the limiters 60 members 7 and 9. The pin 20 being provided with a prick point is adapted to be inserted into the handle 11 and held in place by the collar 19. The piece 21 is provided with two removable prick points 22 and 23 which are in turn adapted to be inserted into 65 the center holes of the two pins 13 and 14 of bar 2, 14 and 15 of bar 3, 15 and 16 of bar 4, etc. The rounded lugs 24 and 25 are provided for the purpose of having the instrument stand horizontally at some distance 70 above the plane of the paper, when in use, in order to facilitate the piercing of the prick pins 20, 22 and 23 exactly through the required points.

Let us now assume that it is desired to 80 divide an angle into four equal parts. Referring to Fig. 4, let ABC be the given angle, which is to be divided into four equal parts. The pins 22 and 23 are now inserted into the central holes of the pins 15 and 16 corresponding 85 to the bar 4. The pin 23 is placed over the point B while the pin 22 is placed on the line BC at the point d so that the center line of the bar 4 coincides with the line BC and the points of the pins are pricked into the paper making the 90 bar rigidly fixed. The pin 20 is now brought upon the line AB falling at point A and the point of the pin is pricked into the paper to fix it. The angle dAB is $\frac{1}{4}$ th of the angle 95 ABC.

Proof:

Distance $Aa=ab=bc=cd=dB$.
Angle $dAB=abA$; angle $cab=acb=2 \times dAB$.

Angle $cbd=cdb=dAB+acb=3 \times dAB$.
Angle $ABC=Bcd=dAB+cdb=4 \times dAB$.

Therefore angle dAB is $\frac{1}{4}$ th of angle ABC.

It will now be evident that the same principle may be used for dividing the angle 105 into any even number of equal parts, except that the pins 22 and 23 are inserted into the central holes of the bar corresponding to the number of divisions required. For example, if six divisions are required the sixth 110 bar from the vertex is used, if eight divisions are required the eighth bar is used, etc.

If it is required to divide a given angle into an odd number of equal parts the procedure is as follows. Referring to Fig. 5, let it be required to divide the angle ABC into five equal parts the distance Bd equal to the distance between the centers of the holes in any of the bars is laid off on BC, and the line dE is drawn parallel to the line AB. The pins 22 and 23 are now inserted into the central holes 15 and 16 of the bar 4, the number of bar being one less than the number of required divisions, while the two pin points are pricked into the paper at points B and d thus making bar 4 coincide on its center line with line BC. The pin 20 is now brought upon the line dE falling at point E and is pricked into the paper. The angle BEd or ABE is the required angle.

20 Proof:

$$\text{Angle } dEB = aBE; \text{ angle } bac = bca = 2 \times dEB.$$

$$\text{Angle } dbc = cdb = dEB + bca = 3 \times dEB.$$

$$\text{Angle } dcB = cBd = dEB + cdb = 4 \times dEB.$$

25 But angle $dEB = ABE$; hence angle $cBd = 4 \times ABE$, and angle $ABC = ABE + cBd = 5 \times ABE$.

Therefore angle ABE is $\frac{1}{5}$ th of angle ABC.

30 From the above example it is evident that for any other odd number of divisions the number of bar to be fixed upon the side BC must be one less than the number of required divisions. For example, if seven divisions are required the sixth bar from the vertex is to be used, if nine divisions are required the eighth bar is used, etc.

It was so far shown how to polysept an acute angle. If it is desired to polysept an 40 obtuse angle, say into n parts, then referring to Fig. 4, where CBD is the given angle, we have:

$$\text{Angle } CBD = CB - 90^\circ$$

and

$$\frac{CBD}{n} = \frac{CBF}{n} + \frac{90^\circ}{n}.$$

50 Therefore if the line BF be drawn and the angle CBF be polysepted in the same manner as heretofore described and the angle FBD be then polysepted in the same manner, the sum of the two angles thus found is the required angle. It is therefore evident that my device can be used for polysepting with one operation any given angle between 0° and 90° and with two operations any angle between 90° and 180° .

55 The mechanism herein shown embodies my preferred form, though it may be modified in some degree, however employing the same general principles.

I do not wish therefore to limit myself to the specific mechanism herein shown but 60 wish to include all mechanisms embodying 65 the same principles of my invention.

Having thus described my invention, I claim as new and wish to secure by Letters Patent:

1. A device for polysepting an angle, comprising a pair of external limiting members pivotally connected to each other and a plurality of links interposed between the said limiting members, each one of the said links being pivotally connected to an adjacent link, and all of the said links, except the innermost one toward the point of intersection of the said limiting members, being slidably connected to both of the said limiting members, the said innermost link being pivotally connected to one of the said limiting members and slidably connected to the other limiting member. 70 75

2. A device for polysepting an angle, comprising a pair of external limiting members pivotally connected to each other and a plurality of links of equal length pivotally connected to each other interposed between the said limiting members, each one of the said links, except the innermost one toward the point of intersection of the said limiting members, being slidably connected to both of the said limiting members, the said innermost link being pivotally connected to one of the said limiting members. 80 85

3. A device for polysepting an angle, comprising a pair of external limiting members pivotally connected to each other and a plurality of links of equal length interposed between the said limiting members, each one of the said links being pivotally connected to an adjacent link, and all of the said links, except the innermost one toward the point of intersection of the said limiting members, being slidably connected to both of the said limiting members, one 90 95 end of the said innermost link being pivotally connected to one of the said limiting members at a distance from the intersection of the said limiting members equal to the length of one link between its pivot centers, 100 while the other end is slidably connected to the other limiting member. 110

4. A device for polysepting an angle, comprising a pair of external limiting members pivotally connected to each other and a plurality of links interposed between the said limiting members, each one of the said links, except the extreme end ones, being pivotally connected at each of its extremities to an adjacent link and slidably connected to both of the said limiting members at its points of intersection with the adjacent links. 115 120

5. A device for polysepting an angle, comprising a pair of external limiting members pivotally connected to each other and a plurality of links of equal length interposed between the said limiting members, each one of the said links, except the extreme end ones, being pivotally connected 125 130

at each of its extremities to an adjacent link and slidably connected to both of the said limiting members at its points of intersection with the adjacent links, thereby forming a plurality of isosceles triangles.

6. A device for polyseeting an angle, comprising a pair of slotted external limiting members pivotally connected to each other and a plurality of links pivotally connected to each other interposed between the said limiting members, each one of the said links except the innermost one toward the point of intersection of the said limiting

members, being adapted to have its pivot pins at its extremities slide in the slots of 15 both of the said limiting members, thereby forming a plurality of triangles of variable altitudes.

Signed at New York, county of New York and State of New York, this 7th day of 20 January, 1915.

DAVID KAPLAN.
